COMBINED EXHAUST FAN AND HOUSING

John Maynard Morrison, Carss Park, near Sydney, New South Wales, Australia, assignor to Centriflo Pty. Limited, Brighton-le-Sands, near Sydney, New South Wales, Australia, a company of Australia

Filed May 29, 1962, Ser. No. 70,342

Term of patent 14 years

(Cl. D62—4)

FIG.1.

FIG. 2.

FIG. 3.

FIG. 1 is a side perspective view of a combined exhaust fan and housing showing my new design.

FIG. 2 is a front perspective view thereof, the rear being substantially the same in appearance.

FIG. 3 is a perspective view of the side opposite that shown in FIG. 1.

I claim:

The ornamental design for a combined exhaust fan and housing, as shown and described.
